UNITED STATES PATENT OFFICE.

THOMAS MIDGLEY, JR., OF WORTHINGTON, OHIO, ASSIGNOR TO THE NATIONAL CASH REGISTER COMPANY, OF DAYTON, OHIO, A CORPORATION OF OHIO, (INCORPORATED IN 1906.)
INVENTOR: THOMAS MIDGLEY, JR., OF WORTHINGTON, OHIO.
INVENTION: INDICATING MECHANISM.

Specification of Letters Patent. Patented Aug. 10, 1915.

1,149,386.

Application filed October 13, 1913. Serial No. 794,816.

To all whom it may concern:

Be it known that I, THOMAS MIDGLEY, Jr., a citizen of the United States, residing at Worthington, in the county of Franklin and State of Ohio, have invented certain new and useful Improvements in Indicating Mechanism, of which I declare the following to be a full, clear, and exact description.

This invention relates to accounting machines and the like and more particularly to novel differential mechanism for setting an accounting device thereof.

The principal object of the invention is to construct the setting mechanism for an indicator so that the latter will be adjusted directly from one indicating position to another during the entire movement of a driving member having an invariable extent of movement. It is not new with this applicant to drive the elements of the totalizer a constant predetermined duration of time regardless of the extent of movement imparted to the elements but the problem of so driving an indicator from one position directly to another presents further difficulties inasmuch as an indicator is turned backwardly as well as forwardly to different extents whereas in machines in which the totalizer elements are driven during the constant movement of the operating mechanism the elements are driven in but one direction by differential mechanism when the mechanism is under the control of amount keys.

Adjustment of the indicators throughout a constant predetermined movement of an operating member makes the operation of the machine much smoother in action and at the same time distributes the amount of work required to drive the indicator over the entire effective stroke of the driving member for setting the indicator and in this way makes the operation of the machine easier and distributes the strain and the wear on the parts of the machine, due to frictional or other forces.

While in the illustrative form shown in the drawings the differential mechanism is disclosed as driving an indicator it will be obvious that the invention can be also employed with but slight variations to drive a totalizer or type carriers and it is intended that the term "accounting element" as used in some of the claims appended hereto should cover all such devices. To accomplish this object in the preferred form of embodiment an indi-

cator setting gear constantly meshes with a pinion rigid with a rotary indicator and the setting gear is pivotally carried by a plate loosely mounted on the shaft supporting the indicating element. Suspended from this plate is a member which will be termed herein as a "floating member" and this member consists of a circular ring-shaped portion and an arm, and the arm is loosely connected to the plate. A disk having a curved slot carries three equidistant and laterally projecting pins equipped with antifriction rollers which ride on the inner periphery of a ring-shaped portion of the floating member. A shaft passes through the slot in the disk and a lever loosely mounted on the shaft and beside the disk carries a pin also passing through the slot in the disk. After an amount key is depressed and upon operation of the operating mechanism differential mechanism is actuated an extent determined by amount keys, and the setting gear for the indicator upon movement of this differential mechanism is caused to roll about the pinion rigid with the indicator as the latter during this movement of the differential mechanism is locked against movement by an alining pawl. The plate supporting the setting segment gear and the floating member is in this manner rocked forward to lower the floating member. The alining pawl for the indicator is then rocked out of engagement with the pinion rigid with the indicator and the lever beside the slotted disk is subsequently given an oscillatory movement. Movement of the lever to an invariable extent in one direction causes movement of the floating member and movement of the plate supporting the floating member and thereby effects rotary movement of the indicator setting segment gear to set the indicator directly from its indicating position at the end of the previous operation of the machine to the desired position at the present operation and the entire movement of the lever in this one direction is utilized for this purpose. Such movement of the driving lever because of the construction of the slot and by engagement of the ends of the lever with pins projecting from the floating member moves the slotted disk and its supporting floating member to a constant position in which position the shaft passing through the slot in the disk is at the geometrical center of the

disk so that upon return movement of the lever to normal position the disk will be turned without effecting the position of the floating member. Finally return movement 5 of the key controlled differential mechanism to zero position causes the indicator setting gear to again roll about the pinion rigid with the adjusted indicator, the alining pawl having been returned to locking engagement 10 with the pinion before the return movement of the differential movement is begun.

With these and incidental objects in view, the invention consists in certain novel features of construction and combinations of 15 parts, the essential elements of which are set forth in appended claims and a preferred form of embodiment of which is hereinafter specifically described with reference to the drawings which accompany 20 and form part of this specification.

Of the drawings, Figure 1 is a transverse vertical section taken through a machine having the present invention applied thereto and showing the key controlled differential 25 mechanism and the operating mechanism in their normal positions and the indicator in its zero position. Fig. 2 is the same as Fig. 1 but shows the indicator in zero position with the alining pawl for the indicator out 30 of engagement therewith and the key controlled differential mechanism is shown in the position in which it is after it has been disconnected from the operating mechanism by the depressed nine key. Fig. 3 is the 35 same as Fig. 1 and shows the key controlled differential mechanism in the position shown in Fig. 2 with the indicator in its nine position and the alining pawl in locking position. Fig. 4 is a detail of the differential mechanism, indicator and part of the operating 40 mechanism shown in Fig. 1 and shows the key controlled differential mechanism and operating mechanism in normal position, and the indicator in its nine position. Fig. 45 5 is a front elevation of Fig. 1 with the key board and the operating cams removed. Fig. 6 is a detail of a cam and an arm for operating the alining pawls for the indicator.

50 Described in detail and with reference to the drawings the illustrative register with the improvements embodied consists of a plurality of banks or sections and each bank forms a unit and the number of banks depends upon the registering capacity desired. One of these sections is shown in the figures and but one section will be described, it being understood, of course, that the other sections are merely duplicates. The driving 55 shaft 1 is given a complete rotation clockwise on every operation of the machine either by means of a manually operated handle or by means of a motor as desired. Attached to the shaft 1 is a plurality of 60 cams 2, (Fig. 1) a pair of cams being pro-

vided for each bank or section of the machine. A three armed lever 3 journaled on a stub shaft 4 in a frame 5, which is carried by rod 6, and shafts 7 and 12 carries at its lower arms oppositely extending rollers 8. 70 There is one of these plates or frames 5 for each bank or section of the machine and each frame supports various parts of the machine for its bank or section, as will be described. Each of the rollers 8 rides on the face of 75 one of the pair of cams 2 provided for that particular bank. The shape and arrangement of a pair of these cams 2 is such that on every rotation of the shaft 1 the lever 3 will be rocked first clockwise retained in this 80 position for approximately one-half rotation of the shaft and finally rocked counter-clockwise to normal position.

Loosely mounted on a stub shaft 9 extending from the frame 5 is a plate 10 for each bank of the machine. A link 11 (Fig. 1) connects this plate and the upper arm of the lever 3 so that when the lever 3 is rocked in the manner just described the plate 10 will also be rocked about its pivot 9 and as the link connects the plate 10 and the lever 3 above their respective centers, the plate always rocks with the lever first clockwise and then counter-clockwise. Loosely mounted on the screw 9 and adjacent the plate 10 is an arm 13. The enlarged portion 14 of the arm 13 is in the form of a sector with its teeth 15 in fixed engagement with the teeth of a segment gear 16 which is pivoted at 17 to the frame 5. Attached to the forward end of the arm 13 by the pivots 19 is a link 20 and a bell crank lever 21. This link and the bell crank lever carry on pivots 22 a latch 23 which is at all times drawn rearward by a spring 24 so that the rear end of the latch 23 is normally held in engagement with a cut 25 in the plate 10, establishing an operative connection between the plate 10 and the arm 13 so that the two will move together as long as the latch 23 remains in engagement with the cut 25 in the plate. Unless a key in the bank is depressed the latch 23 is withdrawn from the cut 25 in the plate 10 at the very beginning of the operation of the machine by a pawl 27 which is pivoted at 28 to the lower end of a plate 29, and at all times urged by a spring (not shown) into the position shown in Fig. 1, with its nose 30 resting in the path of a block 31 rigidly secured to the forward end of the bell crank 120 lever 21. When the plate 10 is rocked clockwise by an operation of the driving mechanism the arm 13 and the parts pivoted thereto will, owing to the fact that the latch 23 is at the time seated in the cut 25, also start 125 to move clockwise. However, the nose 30 on the pawl 27 acting against the block 31 attached to the bell crank 21 will rock the bell crank and the link 20 on their pivots 19 drawing the latch 23 out of engagement with 130

the cut 25 and projecting the forward end 33 of the latch into the lowest one of the notches 34 in the plate 29 secured to the key frame. This stops further upward movement of the arm 13 and latch 23, and downward movement of these parts because of gravitation is prevented by the rear end of the latch 23 riding on the periphery 36 of the plate 10. After the latch 23 is disconnected from the plate 10 the latter continues to the end of its clockwise movement independent of the plate 13 and then later swings back toward normal position. When, during this return movement, the cut 25 in the plate 10 is brought opposite the rear end of the latch 23 the spring 24 draws the latch into engagement with the cut 25 and the arm 13 and its attached parts are returned to their normal position, as shown in Fig. 1. While the spring 24 is depended upon to seat the latch 23 in the cut 25, additional means are provided positively to insure the return of the parts if the spring 24 should become ineffective through any cause. To accomplish this result the portion 37 of the plate 10, above the cut 25, projects beyond the periphery 36 of the plate below the cut so that as the plate 10 returns to its starting point this extending portion 37 will engage the rear end of the latch 23 and draw it downward. The notches 34 and the forward end 33 of the latch 23 are so shaped that as soon as this downward movement of the latch begins the latch is cammed rearward into the cut 25 and the parts involved are all carried by the completion of the operation to the positions they occupied before the operation was begun.

The lowest notch 34 in the plate 29 and into which the latch 23 was projected when no amount key is depressed, as just described, is a zero notch. The notch next above it is the one that the latch 23 engages when one is to be registered and so on up to the top notch, which is the one engaged by the latch 23 when nine is to be registered. When an amount is to be registered the position taken by the latch 23 is determined by the keys 38. These keys are mounted radially to the stub shaft 9 in a frame 39 supported by cross bars 40 extending through the machine. Lateral movement of the keys is prevented by guide plates 43 secured to the frame 39 and so arranged that the keys are free to move end-wise an extent in one direction determined by the heads of the keys and in the other direction by the shoulder 41 of the keys engaging the under side of the plate 44 forming part of the frame 39. In the accompanying drawings the devices for latching the keys in their depressed position until they have served their purpose, mechanism for releasing the key latches and the usual springs for returning the keys to normal position have

been left out. These features are omitted, however, only to make the drawings more easily read and it is to be understood that the machine is provided with these means.

Adjacent the bank of keys is a plate 45 swung from a link 46 and a pawl 47 pivotally attached at 48 and 49 respectively to the key frame 39. Pins 50 on this plate 45 extend laterally under the keys 38. The pawl 47 has a finger 52 which engages a stud 53 on the pawl 27. When any one of the keys 38 is pressed in the cam surface 54 on its lower edge will act against the opposed pin 50 and force the plate 45 down thereby swinging the arm 46 and the pawl 47 about their pivots and causing the finger 52 of the latter acting against the stud 53 on the pawl 27 to draw the pawl 27 back so that its nose 30 will be carried out of the path of the block 31 attached to the bell crank 21. The key is then retained in depressed position partly by the pin 50 engaging the notch 55 on the lower edge of the key but mainly by the latching devices mentioned above but which are not shown in the drawings. As shown in Figs. 2 and 3 the depth of the notch 55 is such that when the key is retained in its fully depressed position the plate 45 is locked down and the nose 30 of the pawl 27 is held back out of the path of the block 31 secured to the bell crank 21. This permits the arm 13 to be carried up by the plate 10 until the block 31 strikes the inwardly projecting end of the depressed key when the latch 23 is disengaged from the cut 25 in the plate 10 and projected into the notch 34 corresponding to the key depressed. On the return of the plate 10 the plungers 23 in the plate 10 are engaged and the parts returned to normal position as described above in connection with the operation of the machine when no key in the bank was depressed. As soon as the plate 10 and the arm 13 reach their normal positions the plate 45 is depressed by key releasing devices (not shown but mentioned above) and the key is restored by its spring (not shown) permitting a spring (not shown) to restore the pawl 27 and the plate 45 to the position shown in Fig. 1.

The segment gear 16 is pivotally connected at 57 to one end of a link 58 which at its opposite end is connected at 59 to a segment gear 60. The segment gear meshes with a pinion 61 rigid with a rotary indicator 62 and the segment gear is pivoted at 63 to a plate 64 which in turn is loosely mounted on a shaft 65 supporting the indicator 62. Fast to a shaft 67 extending longitudinally through the machine is an alining pawl 68, the nose 69 of which normally engages the teeth of the pinion 61 to lock the indicator against movement. Near one end of the shaft 67 (Fig. 1) is a downwardly projecting arm 70 which at its lower

end carries a pin 71 passing through a slot 72 formed in the upper end of an arm 73 which is loosely mounted on the shaft 7. Loosely mounted in the shaft 7 but rigid with the arm 72 is an arm 74 (Fig. 6) and the arm 74 at its free end carries a roller 75 which plays in a cam groove 76 formed on the face of a disk 77 which is fast to the main drive shaft 1. This cam through the above described connections is adapted to rock the alining pawl 68 out of and into engagement with the pinion 61 at the proper times.

The plate 64 is loosely secured by the screw 78 to the upper end of an arm 79 extending vertically upward from the outer periphery of a ring-shaped member 80. This arm 79 together with the ring-shaped portion 80 comprises what was referred to in the general description of the machine as a "floating member" and that term will also be used throughout the specification. The inner periphery of the ring-shaped portion 80 of the floating member is concentric with the outer periphery of the member. The periphery of a circular disk 81 shown in dotted lines in Figs. 1, 2 and 3, is greater than the inner periphery of the ring-shaped portion 80 of the floating member, but less than the outer periphery of this portion of the floating member and the disk carries three pins 83 which project from the right hand side face of the disk and are arranged equidistant from each other, so that the anti-friction rollers with which the pins are equipped ride freely on the inner periphery of the ring-shaped portion 80 of the floating member. The pins 83 are provided with heads 84 to hold the disk in place on the member, there being sufficient space between the disk and the heads of the pins to permit rotary movement of the disk without undue friction between the disk and the floating member. The disk 81 is also provided with a curved slot 85 and the slot is shaped like an inverted S and the curvature of its lower portion is greater than that of the upper portion. A rock shaft 12 which is supported by suitable bearings in the end frames of the machine and in turn supports the frames 5, passes through the S-shaped slot 85 in the disk 81. Rigidly mounted on a sleeve 88 (Figs. 4 and 5) surrounding the shaft 12 is a lever 89 (Figs. 1 to 5) and the lever is mounted just to the left of the disk 81. The oppositely extending arms of the centrally mounted lever 89 are parallel and normally are nearly horizontal. A stud 91 extending below the shaft 12 from the enlarged central portion 92 (best shown in Fig. 4) of the lever 89 also passes into the curved slot 85 in the disk 81. Fast to the left hand end of the sleeve 88 (Fig. 5) is a gear wheel 93 (Figs. 1, 2, 3 and 5) meshing with a segment gear 94 rigidly secured to the left

hand end of a sleeve 95 surrounding the longitudinal shaft 7. Fast to the opposite end of the sleeve is a forwardly and downwardly extending arm 96 which at its lower end carries an anti-friction roller 97 working in a cam groove 98 (Figs. 1, 2 and 3) formed in the face of a disk 99 rigidly mounted on a drive shaft 1.

It is thought that the construction and arrangement of the above described parts have been fully set forth, but to make clear the operation of these parts, their specific operation when the indicator is moved from a lower indicating position to a higher indicating position will first be described and then the specific operation of the parts when the indicator is moved from a higher to a lower indicating position will be taken up. It is desirous to bring out these different operations as the operation of the parts is peculiar and different from each other when the indicator is moved to different extents and in different directions although the entire forward stroke of the segment gear 94 is always utilized to set the indicator. As the drawings show the different positions of the above described parts during an operation of the machine to move the indicator from zero indicating position to nine indication position, this operation may be taken as an example of the operation of the parts when the indicator is moved from a lower to a higher indicating position.

In Fig. 1 the differentially movable arm 13, the lever 89 and the driving segment 94 are shown in normal position and the indicator 62 as indicated by the reference character 100 is in its zero indicating position. With these parts in these positions the shaft 12 is at the geometrical center of the circular disk 81. The nine key is first depressed and subsequently the main drive shaft 1 is given one complete rotation. During approximately the first one-fourth rotation of the main drive shaft 1 the plate 10 is driven upward by the driving cams 2 through the medium of the lever 3 and the link 11. Such movement of the plate 10 carries the differential arm 13 upward until the latch 23 engages the end of the operated nine key and the rear end of the latch is then withdrawn from the cut 25 in the plate 10, after which the plate continues its invariable movement to the extreme limit of its upward movement. This movement of the differential arm 13 effects counterclockwise movement of the segment gear 16 about its pivot 17 and as the indicator 62 is locked from movement by the alining pawl 68 at this time the indicator setting segment gear 60 is caused to roll forwardly under and about the indicator pinion 61 thereby causing clockwise movement of the plate 64 about the shaft 65 as a pivot. In this movement of the plate 64 the pin 63 serves as a moving pivot.

for the segment gear 60 and the segment gear is rocked clockwise about this pivot. The floating member 80 with the disk 81 is thereby lowered nine degrees of movement 5 and portions of the upper portion of the slot 85 are carried into engagement with the shaft 12 and through the stud 91 this causes the disk to rotate slightly in a clockwise direction during the downward movement 10 of the disk as the lever 89 carrying the stud 91 is not at this time moved. Fig. 2 shows these elements in the positions just stated at the end of the up stroke of the plate 10 in which position the plate remains until after 15 the indicator is set to its proper position. After the plate 10 reaches this extreme limit of upward movement the cam groove 76 (Fig. 6) through the arms 73 and 74 rocks the arm 70 and shaft 67 clockwise to raise the alining pawl 68 out of locking engagement with the indicator pinion 61. The lever 89 is now 20 given one complete rotation in a clockwise direction by the segment gear 94. This segment gear, it will be remembered, meshes with the gear 93 secured to the sleeve 88 carrying 25 the lever 89 and is driven by the cam groove 98 acting through the arm 96 rigid with said gear. Because of the resistance afforded by the shaft 12, the clockwise movement of the lever 89 and pin 91 carried 30 thereby will cause the disk 81 to turn in the same direction. Toward the end of said clockwise rotation, the rearwardly extending arm of the lever 89 engages a stud 102 projecting from the lower end of the floating member 79 forcing the floating member and disk 81 forward to a constant position. In this constant position the shaft 12 is again at the geometrical center of the disk. 35 This obviously will occur from the following observation. When the lever 89 is turned the shaft 12 serves as a pivotal center for the disk 81 and the stud 91 on the lever 89 by contacting with the forward side 40 of the slot 85 forces the disk to rotate about the shaft as a center. The disk 81 in this way serves as an eccentric for the floating member and as the disk 81 is turned the floating member is raised since the pivotal 45 center of the disk 81 is above its geometrical center. At the same time that the floating member is raised it is also being swung toward the front of the machine about its pivot 78. Such movement of the floating member 50 toward the front of the machine carries the stud 101 into the path of movement of the forwardly extending arm of the lever 89 and the lever thereby upon reaching the stud forces the floating member to 55 move back toward the rear of the machine. This return movement toward the rear of the machine is permitted because if a straight line should be drawn through the ends of the slot 85 the line would gradually 60 approach a horizontal position. The slot

85 is constructed to facilitate this movement of the disk 81 and floating member 80 toward the rear of the machine as the slot 85 is so curved that as the lever 89 continues to rotate after its arm engages the stud 101 70 the floating member and the disk move to the rear without effecting any practical rotation of the disk, the line between the centers of the shaft 12 and the stud 91 gradually assuming the same direction as those 75 portions of the slot 85 which are between the different contact points of the shaft 12 and the stud 91 with the sides of the slot as the disk is being moved to the right. Fig. 3 shows the position of the floating member 80 and the disk 81 at the end of the clockwise movement of the lever 89, but as the disk 81 is not appreciably rotated after the lever 89 80 engages the stud 101 the position of the slot 85 shown in this figure is approximately the same as its position when the stud is engaged by the lever. The floating member 80 together with the disk 81 is given its last increment of upward movement after the lever 89 contacts with the stud 101 as the disk 81 in moving to the right carries the slot 85 so that the rear end of the slot (Fig. 3) is taken out of engagement with the shaft 12 and stud 91 and moved so that the shaft 95 is at the geometrical center of the disk, and since the rear end of the slot is higher, that is nearer the pivot 78 of the floating member than is the center of the slot, this movement of the disk 81 to the rear forces the floating member to continue its upward 100 movement. When the lever 89 reaches the limit of its clockwise movement both the normally forwardly and rearwardly projecting arms of the lever 89 are in engagement with their respective studs 101 and 102, 105 on the floating member and in this position of the floating member the shaft, as above stated is, at the geometrical center of the disk 81. It can therefore be seen that the entire clockwise stroke of the operating 110 lever 89 is utilized to move the disk 81 and the floating member and therefore the plate 10 and 64 to a constant position.

As the segment gear 60 is retained in its adjusted position during the operation of 115 the lever 89 just described and as the indicator is free to move, the alining pawl 68 having been rocked out of alining position by the upward movement of the plate 64 to a 120 constant position rocks the segment gear 60 about its pivot 63 in a clockwise direction and at the same time causes the pivot 63 of the gear to describe an arc about the indicator shaft 65 as a center and in this manner the indicator is adjusted from its zero 125 position directly to its nine position. During this movement the pin 59 serves as a point about which the segment gear 60 turns, 130 the link 58 being allowed to be lowered about its pivot 57 and the gear therefor has a com-

pound movement. The alining pawl 68 is then rocked back to normal locking engagement with the indicator pinion 61 by its cam 76 and the lever 89, through the intermeshing gear 93 and segment gear 94, is turned back to normal position without affecting the position of the floating member as the shaft 12 is now at the pivotal as well as the geometrical center of the disk 81 10 and the turning of the lever 89 merely results in a similar turning of the disk.

During approximately the last one-quarter rotation of the main drive shaft 1 and after the lever 89 is restored to normal position the plate 10 and the differential arm 13 are also restored to their normal position and the segment gear 16 is in its turn turned clockwise to normal position. As the indicator 62 is again locked against rotation upon the 20 turn movement of the segment gear 16 to normal position the indicator setting segment gear 60 is forced to roll about the pinion 61 and the pivot 63 for the segment gear 60 is carried rearward thereby raising the 25 floating member and the disk 81. The position of the parts of the machine after the operation just described has been performed is shown in Fig. 4 in which position they remain until at the beginning of the next operation of the machine.

As Fig. 4 shows the differential arm 13 in its home or normal position and the indicator in its nine position this position be indicated by the numeral "9" on the indicator, the reverse of the operation just described, that is movement of the indicator from its nine to its zero position, will be taken to illustrate the operation of the machine when the indicator is moved from a 30 higher to a lower indicating position. In this case no amount key 38 is depressed and the zero pawl 27 operates the latch 23 to disconnect the differential arm 13 from the plate 10 so that movement of the plate 10 is 40 effected unaccompanied by the arm 13. After the plate has been given its full extent of upward movement the alining pawl 68 is rocked out of engagement with the pinion 61 rigid with the indicator and the lever 89 is then given its one-quarter rotation in a 45 clockwise direction. The radius of the lower portion of the slot 85 is less than the radius for the upper portion of the slot. This difference in the curvature of the upper and 50 lower portions of the slot is provided as the stud 91 carried by the lever 89 is normally below the shaft 12 and when the floating member is raised so that the shaft 12 is below the geometrical center of the disk 81 55 (Fig. 4) the stud 91 is nearer the periphery of the disk than is the shaft 12, whereas when the floating member is lowered the same extent above the geometrical center of the disk, the shaft is nearer the periphery 60 of the disk than the stud, but it is then the

same distance from the periphery as it is when the floating member is raised. If the lower portion of the slot 85 was of the same radius as the upper portion it can be seen that after the rearwardly extending arm of the lever 89 picks up the stud 102 and then tends to move the floating member toward the front of the machine that the slot would not be constructed to permit the disk 81 to move freely in lateral direction and at the 75 same time in a rotary direction, the upper portion of the slot being constructed to allow simultaneous movement when the disk is elevated because the stud 91 is then nearer the center of the disk than is the shaft 62. 80 But as the radius of the lower portion of the slot is less than the upper portion and as the stud is nearer the lower end of the slot the floating member would be drawn down past the position shown in Figs. 1 and 3 before the rearwardly extending arm of the lever 89 engaged the stud 102 and then it would be moved up to this constant position if it were not for the fact that the position of the slot relative to the stud 91 and shaft 90 86 gradually changes before the arm of the lever 89 engages the stud 102. The curvature of the lower portion of the slot is constructed to permit the bodily movement of the disk 81 downward and to the rear of the 95 machine during its rotary movement so that the pivotal center of the disk is gradually changing. Then when the lever 89 engages the stud 102 the floating member and the disk 81 are moved still farther downward 100 and toward the rear to normal position and this movement given by the engagement of the lever with the stud 102, because of the shape of the slot 85, pulls the floating member downward its last increment of movement to its constant position shown in Figs. 1 and 3. The plate 10 is then restored to 105 normal position and upon reaching zero position the latch 23 is pulled rearward to couple the arm 13 again with the plate. When the floating member and disk 81 were so pulled downward to their constant position the alining pawl 68 was out of locking engagement with the pinion 61 so that the segment gear 60 was forced to rock counter-clockwise to move the indicator from its nine to its zero position. The position of the parts of the machine after the operation so far described is shown in Fig. 1.

It will be clear from the above described operations that when the indicator is set at any other positions than nine and zero, the mechanisms will be given intermediate positions between those positions specified in the above descriptions. For example, at the end of the operation of the machine when the indicator is not in its nine or zero position the disk 81 and floating member are always in such position that the shaft 12 is below the geometrical center of the 130

disk 81 (Fig. 1), and above the position of the shaft shown in Fig. 4.

While the form of mechanism herein shown and described is admirably adapted to fulfil the objects primarily stated, it is to be understood that it is not intended to confine the invention to the one form of embodiment herein shown and described, as it is susceptible of embodiment in various forms, all coming within the scope of the claims which follow.

I claim—

1. In a machine of the class described, the combination with an indicator adapted to be adjusted directly and in either direction from one indicating position to another; of an actuator constantly in engagement therewith; a driving member for the actuator, having an invariable extent of movement; and connections between the driving member and the actuator whereby the indicator is driven from one indicating position to another, the entire invariable extent of movement of the driving member being always utilized for this purpose.

2. In a machine of the class described, the combination with an indicator adapted to be moved directly and in either direction from one indicating position to another; and means for always driving the same directly from one indicating position to another throughout a constant predetermined duration regardless of the extent of movement imparted thereto.

3. In a machine of the class described, the combination with an indicator; and actuating means constantly in engagement therewith for driving the indicator directly and in either direction from one indicating position to another throughout a constant predetermined duration regardless of the extent of movement to be imparted to the indicator.

4. In a machine of the class described, the combination with an indicator adapted to be moved from one indicating position directly to another indicating position; of a pivoted actuator constantly in engagement therewith; means for effecting differential bodily movement of the actuator without affecting the indicator; and means for subsequently effecting differential rotation of the actuator about its pivot to drive the indicator from one indicating position to another.

5. In a machine of the class described, the combination with an accounting element; of a pivoted actuator therefor; means for effecting differential bodily movement of the actuator; and means for subsequently effecting bodily movement and rotary movement of the actuator and thereby position the accounting element.

6. In a machine of the class described, the combination with an accounting element; of a pivoted actuator therefor constantly in

mesh therewith; means for effecting differential rolling movement of the actuator about the accounting element without affecting the accounting element; and means for subsequently effecting differential rotary movement of the actuator about its pivot to drive the accounting element.

7. In a machine of the class described, the combination with an accounting element; of an actuator therefor, adapted to be given two kinds of movement; means for imparting differential movement of one kind to the actuator without affecting the accounting elements; and means for subsequently effecting differential movements of both kinds to set the accounting element.

8. In a machine of the class described, the combination with an accounting element; of a pivoted actuator therefor; means for effecting differential compound movement of the actuator without affecting the accounting element; and means for subsequently effecting differential compound movement of the actuator to position the accounting element.

9. In a machine of the class described, the combination with an accounting element; of a pivoted actuator therefor; means for effecting differential bodily movement of the actuator without affecting the accounting element; and means for subsequently effecting bodily movement of the actuator to a constant position and simultaneously effecting rotary movement of the actuator to position the accounting element.

10. In a machine of the class described, the combination with an accounting element; of a pivoted actuator therefor; and constantly in mesh therewith; means for effecting differential bodily movement of the actuator without affecting the accounting element; and means for subsequently effecting bodily movement of the actuator to a constant position, and simultaneously effecting rotary movement of the actuator to position the accounting element.

11. In a machine of the class described, the combination with a main operating mechanism; of an accounting element; a pivoted actuator therefor; amount determining manipulative means; differential mechanism controlled by said manipulative means and driven by said operating mechanism for giving the actuator a differential bodily movement; and means also driven by the main operating mechanism for subsequently effecting differential rotary movement of the actuator to position the accounting element.

12. In a machine of the class described, the combination with a main operating mechanism; of an accounting element; a pivoted actuator therefor and constantly in engagement therewith; amount determining manipulative means; differential mechanism controlled by said manipulative means and

driven by said operating mechanism for giving the actuator a differential bodily movement; and means also driven by the main operating mechanism for subsequently effecting differential rotary movement of the actuator to position the accounting element.

13. In a machine of the class described, the combination with a main operating mechanism; of an accounting element; an actuator therefor adapted to be given two kinds of movement; amount determining manipulative means; differential mechanism controlled by said manipulative means and driven by the operating mechanism for imparting differential movement of one kind to the actuator; and means also driven by the main operating mechanism for subsequently effecting differential movements of both kinds to set the accounting element.

14. In a machine of the class described, the combination with a main operating mechanism; of an accounting element; an actuator therefor constantly in engagement therewith and adapted to be given two kinds of movement; amount determining manipulative means; differential mechanism controlled by said manipulative means and driven by the operating mechanism for imparting differential movement of one kind to the actuator; and means also driven by the main operating mechanism for subsequently effecting differential movements of both kinds to set the accounting element.

15. In a machine of the class described, the combination with a main operating mechanism; of an accounting element; a pivoted actuator therefor constantly in mesh therewith; amount determining manipulative means; differential mechanism controlled by the manipulative means; differential mechanism controlled by the manipulative means and driven by the operating mechanism for differentially positioning the actuator without affecting the accounting element; and means also driven by the operating mechanism for effecting bodily movement of the actuator to a constant position and simultaneously effecting rotary movement of the actuator to position the accounting element.

16. In a machine of the class described, the combination with an accounting element; of an actuator therefor; and means for simultaneously imparting to the actuator a differential rotary movement and a differential bodily movement to adjust the accounting element.

17. In a machine of the class described, the combination with an accounting element; of an actuator therefor adapted to be given a rotary and a bodily movement; operating mechanism; and means actuated by the operating mechanism for simultaneously imparting to the actuator a differential bodily movement and a differential rotary movement to adjust the accounting element.

18. In a machine of the class described, the combination with an accounting element; of an actuator therefor, constantly in engagement therewith, and means for simultaneously imparting to the actuator a differential rotary movement and a differential bodily movement to adjust the accounting element.

19. In a machine of the class described, the combination with an accounting element; of an actuator therefor adapted to be given a rotary and a bodily movement; operating mechanism; and means actuated by the operating mechanism for simultaneously imparting to the actuator a differential bodily movement and a differential rotary movement to adjust the accounting element, the entire of a constant extent of the movement of the operating mechanism being always utilized for this purpose regardless of the extent of movement imparted to the accounting element.

20. In a machine of the class described, the combination with operating mechanism; of an accounting element; an actuator therefor constantly in engagement therewith and adapted to be given a rotary and a bodily movement; an operating device having a constant extent of movement and actuated by the operating mechanism for simultaneously imparting to the actuator a differential bodily movement and a differential rotary movement to adjust the accounting element, the entire of a constant extent of the movement of said operating device being utilized for this purpose regardless of the extent of movement imparted to the accounting element.

21. In a machine of the class described, the combination with an accounting element; of an actuator therefor; means for locking the accounting element in adjusted position and constructed to be moved out of locking position; means for giving the actuator a differential compound movement while the accounting element is locked; and means for subsequently effecting a second differential compound movement of the actuator after the locking means is moved out of locking position to adjust the accounting element.

22. In a machine of the class described, the combination with an accounting element adapted to be moved forwardly or backwardly to different extents; of a pivoted actuator therefor; means for effecting differential compound movement of the actuator; and means for subsequently effecting a second compound movement of the actuator and thereby move the accounting element forwardly or backwardly to different extents.

23. In a machine of the class described, the combination with an accounting element adapted to be moved forwardly or back-

wardly; of a pivoted actuator therefor constantly in mesh therewith and adapted to drive the accounting element forwardly or backwardly to different extents; means for effecting differential rolling movement of the actuator about the accounting element without affecting the accounting element; and means for subsequently effecting differential rotary movement of the actuator 10 about its pivot to drive the accounting element.

24. In a machine of the class described, the combination with an accounting element; of an actuator therefor, adapted to be given two kinds of movement and constantly in engagement therewith; means for imparting differential movement of one kind to the actuator without affecting the accounting elements; and means for subsequently effecting differential movement of 20 both kinds to set the accounting element.

25. In a machine of the class described, the combination with an accounting element; of a pivoted actuator therefor constantly in engagement therewith; means for effecting differential compound movement of the actuator without affecting the accounting element; and means for subsequently effecting differential compound 30 movement of the actuator to position the accounting element.

26. In a machine of the class described, the combination with an accounting element; of an actuator therefor, adapted to be given two kinds of movement; means for imparting differential movements of two kinds to the actuator without affecting the accounting elements; and means for subsequently effecting differential movement of 40 one kind to set the accounting element.

27. In a machine of the class described, the combination with an accounting element; of an actuator therefor, adapted to be given two kinds of movement and constantly in engagement therewith; means for imparting differential movements of two kinds to the actuator without affecting the accounting elements; and means for subsequently effecting differential movement of 50 one kind to set the accounting element.

28. In a machine of the class described, the combination with an accounting element adapted to be driven either forwardly or backwardly to different extents; of an actuator therefor, adapted to be given two kinds of movement and constantly in engagement therewith; means for imparting differential movements of two kinds to the actuator without affecting the accounting 55 elements; and means for subsequently effecting differential movement of one kind to set the accounting element differentially either in a forward or backward direction.

29. In a machine of the class described, 60 the combination with an accounting element

adapted to be driven forwardly or backwardly to different extents; of a pivoted actuator therefor; means for effecting differential movement of the actuators without affecting the accounting element; and means for subsequently effecting bodily movement of the actuator to a constant position and simultaneously effecting rotary movement of the actuator to position the accounting element. 75

30. In a machine of the class described, the combination with an accounting element constructed to be driven forwardly or backwardly to different extents; of a pivoted actuator therefor and constantly in mesh therewith; means for effecting differential bodily movement of the actuator without affecting the accounting element; and means for subsequently effecting bodily movement of the actuator to a constant position and simultaneously effecting rotary movement of the actuator to position the accounting element either in a forward or backward direction. 80

31. In a machine of the class described, the combination with a main operating mechanism; of an accounting element constructed to be driven either forwardly or backwardly; a pivoted actuator therefor; amount determining manipulative means; differential mechanism controlled by said manipulative means and driven by said operating mechanism for giving the actuator a differential bodily movement; and means also driven by the main operating mechanism for subsequently effecting differential rotary movement of the actuator to position the accounting element differentially in either a forward or backward direction. 95

32. In a machine of the class described, the combination with a main operating mechanism; of an accounting element; an actuator therefor constantly in engagement therewith and adapted to be given two kinds of movement; amount determining manipulative means; differential mechanism controlled by said manipulative means and driven by the operating mechanism for imparting differential movement of both kinds to the actuator; and means also driven by the main operating mechanism for subsequently effecting differential movement of one kind to set the accounting element. 100

33. In a machine of the class described, the combination with an accounting element constructed to be moved forwardly or backwardly to different extents; of an actuator therefor; and means for simultaneously imparting to the actuator a differential rotary movement and a differential bodily movement to adjust the accounting element differentially either in a forward or backward direction. 115

34. In a machine of the class described, the combination with an accounting element 120

constructed to be moved forwardly or backwardly to different extents; of an actuator therefor adapted to be given a rotary and a bodily movement; operating mechanism; and means actuated by the operating mechanism for simultaneously imparting to the actuator a differential bodily movement and a differential rotary movement to move the accounting elements differentially either in 10 a forward or backward direction.

35. In a machine of the class described, the combination with an accounting element constructed to be moved forwardly or backwardly to different extents; of an actuator therefor, constantly in engagement therewith; and means for simultaneously imparting to the actuator a differential rotary movement and a differential bodily movement to adjust the accounting element differentially in either a forward or backward direction.

36. In a machine of the class described, the combination with an indicator adapted to be moved from one indicating position directly to another indicating position; of a pivoted actuator therefor, constantly in engagement therewith; means for locking the indicator in adjusted position and adapted to be disabled; means for effecting differential bodily movement of the actuator while the indicator is locked against movement by said locking means; and means for subsequently effecting differential rotation of the actuator about its pivot after the locking means has been disabled to drive the indicator from one indicating position to another.

37. In a machine of the class described, the combination with a main operating mechanism; of an accounting element; a pivoted actuator therefor, constantly in engagement therewith; means for locking the accounting element in adjusted position and constructed to be disabled; amount determining manipulative means; differential mechanism controlled by said manipulative means and driven by said operating mechanism for giving the actuator a differential bodily movement while the accounting element is locked against movement by said locking means; and means also driven by the main operating mechanism for subsequently effecting differential rotary movement of the actuator after the locking means has been disabled to adjust the accounting element.

38. In a machine of the class described, the combination with a main operating mechanism; of an accounting element; an actuator therefor constantly in engagement therewith and adapted to be given two kinds of movement; means for locking the accounting element in adjusted position and adapted to be disabled; amount determining manipulative means; means controlled

by said manipulative means and driven by the operating mechanism for imparting differential movement of one kind to the actuator while the accounting element is locked against movement by the locking means; and means also driven by the main operating mechanism for subsequently effecting differential movements of both kinds to set the accounting element after the locking means has been disabled. 75

39. In a machine of the class described, the combination with an accounting element; of a pivoted actuator therefor; means for effecting differential bodily movement of the actuator; and operating mechanism having a constant extent of movement for subsequently effecting bodily and rotary movement of the actuator and thereby position the accounting element, the entire constant extent of movement of the operating mechanism being always utilized for this purpose. 80

40. In a machine of the class described, the combination with an accounting element; of a pivoted actuator therefor, constantly in engagement therewith; means for effecting differential rolling movement of the actuator about the accounting element without affecting the accounting element; and operating means having a constant extent of movement for subsequently effecting differential rotary movement of the actuator about its pivot to drive the accounting element, the entire constant extent of movement of the operating means being always utilized for this purpose. 95

41. In a machine of the class described, the combination with an accounting element; of an actuator therefor adapted to be given two kinds of movement; means for imparting differential movement of one kind to the actuator without affecting the accounting element; and operating means having a constant extent of movement for subsequently effecting differential movements of both kinds to set the accounting element, the entire extent of movement of the operating means being always utilized for this purpose. 105

42. In a machine of the class described, the combination with an accounting element; of a pivoted actuator therefor; means for effecting differential compound movement of the actuator without affecting the accounting element; and operating means having a constant extent of movement for subsequently effecting differential compound movement of the actuator to position the accounting element, the entire constant extent of movement of the operating mechanism being always utilized for this purpose. 110

43. In a machine of the class described, the combination with an accounting element; of a pivoted actuator therefor; means

for effecting bodily movement of the actuator without affecting the accounting element; and operating means having a constant extent of movement for subsequently 5 effecting bodily movement of the actuator so that its pivot is moved to a constant position and simultaneously effecting rotary movement of the actuator to position the accounting element, the entire invariable extent 10 of movement of the operating means being always utilized for this purpose.

44. In a machine of the class described, the combination with an accounting element; of an actuator therefor adapted to be 15 given two kinds of movement and constantly in engagement therewith; means for imparting differential movement of one kind to the actuator without affecting the accounting element; and operating means 20 having a constant extent of movement for subsequently effecting differential movement of both kinds to set the accounting element, the entire extent of movement of the operating means being always utilized 25 for this purpose.

45. In a machine of the class described, the combination with an accounting element; of a pivoted actuator therefor and constantly in engagement therewith; means 30 for effecting differential compound movement of the actuator without affecting the accounting element; and operating means having a constant extent of movement of the actuator to position the accounting element, the entire constant extent of movement 35 of the operating mechanism being always utilized for this purpose.

46. In a machine of the class described, the combination with a main operating 40 mechanism; of an accounting element; a pivoted actuator therefor; amount determining manipulative means; differential mechanism controlled by said manipulative means and driven by said operating mechanism for giving the actuator a differential 45 bodily movement; and means having a constant extent of movement and driven by the operating mechanism for subsequently effecting differential rotary movement of the 50 actuator to position the accounting element, the entire invariable extent of movement of the last mentioned means being utilized for this purpose.

47. In a machine of the class described, the 55 combination with a main operating mechanism; of an accounting element; a pivoted actuator therefor constantly in engagement therewith; amount determining manipulative means; differential mechanism controlled by said manipulative means and driven by said operating mechanism, for giving the actuator a differential bodily 60 movement; and means having a constant extent of movement and driven by the operating mechanism for subsequently effecting 65

differential rotary movement of the actuator to position the accounting element, the entire invariable extent of movement of the last mentioned means being utilized for this purpose.

70

48. In a machine of the class described, the combination with a determining member; of a series of keys, means controlled by the keys, for differentially adjusting the determining member; a device having an 75 invariable movement at each operation of the machine; and an element operated by said device an extent determined by the determining member and while said member is in its adjusted position, the entire invariable movement of said device being always utilized for this purpose.

49. In a machine of the class described, the combination with key controlled differential mechanism; of an accounting element; 85 a pivoted actuator therefor; a plate supporting said actuator and differentially moved by said differential mechanism; a member pivoted to said plate and moved differentially with said plate; and a device 90 for moving said plate and member to cause bodily and rotary movement of the actuator and thereby set the accounting element.

50. In a machine of the class described, the combination with key controlled differential mechanism; of an accounting element; 95 a pivoted actuator therefor; a plate supporting said actuator and differentially moved by said differential mechanism; a member pivoted to said plate and moved 100 differentially with said plate; and a device having an invariable extent of movement for moving said plate and member to cause bodily and rotary movement of the actuator and thereby set the accounting element the 105 entire invariable extent of movement of said device being always utilized for this purpose.

51. In a machine of the class described, the combination with key controlled differential mechanism; of an accounting element; 110 a pivoted actuator therefor constantly in engagement therewith; a plate supporting said actuator and differentially moved by said differential mechanism without affecting said accounting element; a member pivoted to said plate and moved differentially with said plate; and a device for moving said plate and member to cause bodily and 115 rotary movement of the actuator and thereby set the accounting element.

52. In a machine of the class described, the combination with key controlled differential mechanism; of an accounting element; 120 a pivoted actuator therefor constantly in engagement therewith; a plate supporting said actuator and differentially moved by said differential mechanism, without affecting the accounting element; a member pivoted to said plate and moved differentially 125

130

with said plate; and a device having an invariable extent of movement for moving said plate and member to cause bodily and rotary movement of the actuator and thereby set the accounting element the entire invariable extent of movement of said device being always utilized for this purpose.

53. In a machine of the class described, the combination with key controlled differential mechanism; of an accounting element; a pivoted actuator therefor; a plate supporting said actuator and differentially moved by said differential mechanism; a member pivoted to said plate and moved differentially with said plate; and a device for moving said plate and member to a constant predetermined position to cause bodily and rotary movement of the actuator and thereby set the accounting element.

54. In a machine of the class described, the combination with key controlled differential mechanism; of an accounting element; a pivoted actuator therefor constantly in engagement therewith; a plate supporting said actuator and differentially moved by said differential mechanism, without affecting the accounting element; a member pivoted to said plate and moved differentially with said plate; and a device having an invariable extent of movement for moving said plate and member to a constant predetermined position to cause bodily and rotary movement of the actuator and thereby set the accounting element, the entire invariable extent of movement of said device being always utilized for this purpose.

55. In a machine of the class described, the combination with key controlled differential mechanism; of an accounting element; a pivoted actuator therefor; a plate supporting said actuator and differentially moved by said differential mechanism; a member pivoted to said plate and moved differentially with said plate; a disk movably mounted on said member and moved differentially with the member; and a device for rotating said disk to move said member and plate and thereby effect bodily and rotary movement of the actuator to set the accounting element.

56. In a machine of the class described, the combination with key controlled differential mechanism; of an accounting element; a pivoted actuator therefor; a plate supporting said actuator and differentially moved by said differential mechanism; a member pivoted to said plate and moved differentially with said plate; a disk movably mounted on said member and moved differentially with the member; and a device having a constant extent of movement for rotating said disk to move said member and plate and thereby effect bodily and rotary movement of the actuator to set the accounting element the entire constant ex-

tent of movement of said device being always utilized for this purpose.

57. In a machine of the class described, the combination with key controlled differential mechanism; of an accounting element; a pivoted actuator therefor; a plate supporting said actuator and differentially moved by said differential mechanism; a member pivoted to said plate and moved differentially with the plate; a disk revolvably mounted on said member, and having a slot; a shaft passing through said slot; a lever on said plate and having a pin projecting into said slot in the disk; and means for rocking said lever an invariable extent to rotate said disk and thereby move said member and plate to effect bodily and rotary movement of the actuator for setting the accounting element.

58. In a machine of the class described, the combination with key controlled differential mechanism; of an accounting element; a pivoted actuator therefor and constantly in engagement therewith; a plate supporting said actuator and differentially moved by said differential mechanism; a member pivoted to said plate and moved differentially with the plate; a disk revolvably mounted on said member, and having a slot; a shaft passing through said slot; a lever on said plate and having a pin projecting into said slot in the disk; and means for rocking said lever an invariable extent to rotate said disk and thereby move said member and plate to effect bodily and rotary movement of the actuator for setting the accounting element.

59. In a machine of the class described, the combination with key controlled differential mechanism; of an accounting element; a pivoted actuator therefor; a plate supporting said actuator and differential mechanism; a member pivoted to said plate and moved differentially with the plate; a disk revolvably mounted on said member, and having a slot; a shaft passing through said slot; a lever on said plate and having a pin projecting into said slot in the disk; and means for rocking said lever an invariable extent to rotate said disk and thereby move said member and plate to effect bodily and rotary movement of the actuator for setting the accounting element, the entire invariable extent of movement of said lever being always utilized for this purpose.

60. In a machine of the class described, the combination with key controlled differential mechanism; of an accounting element; a pivoted actuator therefor constantly in engagement therewith; a plate supporting said actuator and differentially moved by said differential mechanism; a member pivoted to said plate and moved differentially with said plate; and a device for moving said plate and member to a constant pre-

- determined position to cause bodily and rotary movement of the actuator and thereby set the accounting element.
61. In a machine of the class described, the combination with key controlled differential mechanism; of an accounting element; a pivoted actuator therefor constantly in engagement therewith; a plate supporting said actuator and differentially moved by said differential mechanism; a member pivoted to said plate and moved differentially with said plate; a disk movably mounted on said member and moved differentially with the member; and a device for rotating said disk to move said member and plate and thereby effect bodily and rotary movement of the actuator to set the accounting element. 70
62. In a machine of the class described, the combination with key controlled differential mechanism; of an accounting element; a pivoted actuator therefor constantly in engagement therewith; a plate supporting said actuator and differentially moved by said differential mechanism; a member pivoted to said plate and moved differentially with the plate; a disk revolvably mounted on said member, and having a slot; a shaft passing through said slot; a lever on said plate and having a pin projecting into said slot in the disk; and means for rocking said lever an invariable extent to rotate said disk and thereby move said member and plate to effect bodily and rotary movement of the actuator for setting the accounting element, the entire invariable extent of movement of said lever being always utilized for this purpose. 75
63. In a machine of the class described, the combination with an indicator to be differentially moved directly and in either direction from one indicating position to another, and means for operating same, comprising an invariably moved driving device and connections driven thereby throughout the entire invariable movement regardless of the extent or direction of the movement imparted to the indicator. 80
64. In a machine of the class described, the combination with an indicator to be moved directly and in either direction from one indicating position to another, of differential mechanism, an invariably moved driving device, and connections controlled by the differential mechanism and driven throughout the entire invariable movement of the driving device for adjusting the indicator directly and in either direction from one indicating position to another. 85
65. In a machine of the class described, the combination with an indicator adapted to be differentially adjusted directly from one indicating position to another, of an actuator constantly in engagement with the indicator, means for differentially position- 90
- ing said actuator to set up values thereon, a driving device having a constant extent of movement, and connections whereby said driving device will drive the differentially positioned actuator during the entire constant movement of said device whereby to differentially adjust the indicator. 95
66. In a machine of the class described, the combination with a pivotally mounted indicator to be differentially adjusted in either direction and directly from one indicating position to another, of an actuator constantly in engagement with the indicator, means for differentially adjusting the actuator about the pivot of the indicator, a driving device having a constant extent of movement, and connections driven during the entire movement of the driving device for driving the differentially adjusted actuator and thereby differentially adjusting the indicator. 100
67. In a machine of the class described, the combination with an indicator, of a toothed actuator constantly in mesh therewith, means whereby the actuator may be differentially adjusted in either direction to set up values thereon without disturbing the previous indication, driving devices having a constant extent of movement, and connections driven by and during the entire constant extent of movement of said driving devices for operating the differentially adjusted actuator whereby to differentially adjust the indicator. 105
68. In a machine of the class described, the combination with an indicator movable in either direction and directly from one indicating position to another, of an actuator constantly in engagement therewith, and means whereby the actuator may be differentially positioned without disturbing the setting of the indicator to set up on the actuator values to be subsequently shown by the indicator. 110
69. In a machine of the class described, the combination with an indicator, of an actuator constantly in mesh therewith, means for differentially adjusting the actuator to set up thereon the difference between the value shown at the time by the indicator and the value to be subsequently shown, said adjustment being made without disturbing the setting of the indicator, and an independent means for then differentially adjusting the differentially positioned actuator 115 in either direction whereby to set the indicator to show the new value. 120
70. In a machine of the class described, the combination with an indicator, of an actuator constantly in mesh therewith, mechanism for differentially positioning the actuator to set up thereon the difference between the value shown at the time by the indicator and the value to be subsequently shown, means holding the indicator station- 125 130

ary during said adjustment of the actuator, devices for enabling and disabling said means, and independent means for differentially driving the differentially positioned actuator in either direction whereby to set the indicator to show the new value.

71. In a machine of the class described, the combination with an indicating element comprising a pinion, of a toothed actuator 10 constantly in mesh with said pinion, means for differentially adjusting the actuator about the pinion to set up on the actuator the difference between the value shown at the time by the indicator and the value to be

subsequently shown, said adjustment being 15 made without disturbing the setting of the indicator, an invariably moved device, and connections driven throughout the entire movement of said device for adjusting the differentially positioned actuator in either 20 direction whereby to set the indicator to show the new value.

In testimony whereof I affix my signature in the presence of two witnesses.
